MOISTURE SEPARATING DEVICE

Joseph Doucette, Hillside, Ill.

Application February 23, 1940, Serial No. 320,377

2 Claims. (Cl. 183—112)

This invention pertains to new and useful improvements in moisture separating devices and has for its primary object to provide, in a manner as hereinafter set forth, a novel construction and arrangement for expeditiously condensing and removing excess moisture from air.

Another very important object of the invention is to provide a separating device of the aforementioned character comprising novel means for pre-cooling the moisture laden air before it enters the condensing chamber.

Other objects of the invention are to provide a moisture separating device of the character described which will be comparatively simple in construction, strong, durable, highly efficient and reliable in use, compact and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in horizontal section through an apparatus constructed in accordance with the present invention.

Figure 2 is a view in vertical longitudinal section through the device, taken on the line 2—2 of Figure 1.

Figures 3, 4 and 5 are cross sectional views, taken substantially on the lines 3—3, 4—4, and 5—5 of Figure 2.

Figure 6 is a detail view in perspective of one of the condenser baffles.

Referring now to the drawings in detail, it will be seen that the embodiment of the invention which has been illustrated comprises a horizontally elongated tank 1 of suitable material for the reception of water. Connected to one end of the tank 1 is a supply pipe 2. In the other end portion of the tank 1 is a discharge pipe 3 the intake end of which is located adjacent the top of said tank.

Mounted longitudinally in the tank 1 is a metallic cylinder 4. The ends of the cylinder 4 are closed by removable heads 5 and 6.

Extending into the tank 1 at one end thereof is an air pipe 7 from a storage tank. The reference numeral 8 designates cooling coils in the tank 1 having one end connected to the air pipe 7. As best seen in Figure 1 of the drawings, the coils 8 extend around the cylinder 4 and have their other ends connected to the head 5 at the intake end of said cylinder, as at 9. Connected

to the head 6 at the other end of the cylinder 4 and extending through the tank 1 is an air discharge pipe 10. The pipe 10 is connected with a vertical air conduit 11.

5 The lower portion of the cylinder 4 is formed to provide a depending moisture trough 12 which is inclined from the intake end of said cylinder to the discharge end thereof. Mounted in the cylinder 4 is a liner 13 of a highly polished, substantially non-porous metal, such as stainless steel. The lower portion of the liner 13 is provided with a slot 14 which communicates with the trough 12. This is illustrated to advantage in Figure 2 of the drawings.

10 Mounted centrally in the cylinder 4 is a longitudinal rod 15. Suitable supports 16 are provided in the end portions of the cylinder 4 for the rod 15. Mounted at longitudinally spaced points on the rod 15 are adjustable baffles 17.

15 The baffles 17 are also of stainless steel or the like. Notches or recesses 18 are provided in the peripheral portions of the baffles 17 for the passage of air, said notches or recesses in the successive baffles being staggered. A moisture discharge pipe 19 connects the lower end portion of the trough 12 with the conduit 11 at a point below the air discharge pipe 10.

20 It is thought that the operation of the apparatus will be readily apparent from a consideration of the foregoing. Cold water from the supply pipe 2 flows through the tank 1 and is discharged through the pipe 3. The moisture laden air from the reservoir enters the tank 1 from the pipe 7 and flows through the coils 8. Thus, the comparatively warm air is thoroughly cooled before it reaches the intake end of the cylinder 4.

25 When the air contacts the comparatively cold surfaces of the elements 13 and 17 in the cylinder 4 the moisture therein is condensed. As the elements 13 and 17 are substantially non-porous the condensed moisture flows by gravity into the trough 12 from which it is taken by the pipe 19. The air flows through the passages 18 in the baffles 17 and is conveyed from the cylinder 4 to the conduit 11 by the discharge pipe 10. Any suitable number of baffles 17 may be employed and said baffles may be spaced as desired. The non-porous quality of the elements 13 and 17 assures continued maximum efficiency of the device.

30 It is believed that the many advantages of a moisture separating device constructed in accordance with the present invention will be readily understood and although a preferred embodiment of the apparatus is as illustrated and described, it

is to be understood that changes in the details of construction and in the combination and arrangement of parts may be resorted to which will fall within the scope of the invention as claimed.

What is claimed is:

1. A moisture separating device of the class described comprising a horizontal cylinder, a longitudinal, inclined trough depending from the lower portion of the cylinder and communicating therewith, an air intake pipe connected to one end of the cylinder, an air discharge pipe connected to the other end of the cylinder, a moisture discharge pipe connected to the lower portion of the trough, a rod mounted longitudinally in the cylinder, and a plurality of highly polished, substantially non-porous baffles mounted at longitudinally spaced points on the rod, said baffles having air passages in their peripheral portions.

2. A moisture separating device of the class described comprising a horizontal cylinder, a longitudinally extending, inclined trough depending from the lower portion of the cylinder and communicating therewith, air intake and discharge pipes connected with the ends of the cylinder, a moisture discharge pipe connected with the lower portion of the trough, a liner of highly polished, substantially non-porous material mounted longitudinally in the cylinder, said liner having a longitudinal slot therein communicating with the trough for the passage of moisture thereinto, a rod mounted longitudinally in the cylinder, and a plurality of baffles of highly polished, substantially non-porous material adjustably mounted at longitudinally spaced points on the rod, said baffles having air passages in their peripheral portions.

JOSEPH DOUCETTE.
